UNITED STATES PATENT OFFICE

CHARLES W. LAWSER, OF BALA, PENNSYLVANIA, ASSIGNOR TO WICACO MACHINE CORPORATION, OF PHILADELPHIA, PENNSYLVANIA, A CORPORATION OF PENNSYLVANIA

SPINNING PUMP

Application filed December 15, 1926. Serial No. 154,977.

This invention relates to improvements in pumps of the type used in the manufacture of artificial silk for forcing the plastic material through the spinneret.

5 The principal object of the invention is to provide a novel and improved plunger and actuating cam assembly affording advantages of superior strength and durability.

Another object of the invention is to provide a novel operative connection between the plunger-actuating cam and the plungers such that requirement for flexible parts to compensate for changes of relative position between the plungers and the cam is eliminated.

15 A further object of the invention is to provide novel and improved means for adjusting the stroke of the plungers.

In the attached drawings:

Figure 1 shows a longitudinal section 20 through a pump made in accordance with my invention;

Fig. 2 is a detached view of one of the plungers;

Fig. 3 is a plan view of the cam plate, 25 and

Figs. 4 and 5 are side views.

With reference to the drawings, the pump comprises the usual cylindrical casing 1 in which is mounted a rotor 2, the latter including a shaft extension 3 which projects through the cylindrical head 4 of the casing 1 and has attached to its outer end a gear 5 by means of which the rotor 2 is rotated. The casing comprises also a detachable head 35 6 at its opposite end having on the inside a spherical recess or seat 7 for a correspondingly formed cam-supporting member 8. The member 8 has a projection 9 on its under side which projects through a transverse slot

40 10 in the head 6, and has a threaded extremity 11 of reduced diameter which projects beyond the outer end of the head 6 and receives a nut 12. This nut when tightened against the end of the head 6, retains the member 8 in adjusted position in the seat 7. This adjusted position of the member 8 is also maintained by means of a pair of set screws 13 and 14 which are threaded in the head 6 and project from opposite ends into 50 the slot 10, as clearly illustrated, to bear

against opposite sides of the extension 9 of the member 8. By loosening the nut 12 and thereafter adjusting the set screws 13 and 14, the position of the member 8 may be varied as desired, and by tightening the nut 12, the member 8 is locked in the adjusted position.

55 Seated for rotation in the member 8 is a cam 15, cylindrical in form and having at its under side a cylindrical extension 16 which fits into a corresponding recess in the upper face of the member 8, as clearly illustrated. The cam comprises on its upper face a central conical recess 17 in which is seated a ball 18, and pressure is applied to the ball through a rod 21 mounted in the rotor 2 and adjustable longitudinally of the rotor from the exterior of the casing.

60 In the present instance the rod 21 occupies a central passage 20 extending completely through the rotor from end to end, and the outer end 36 of the rod is threaded in the countersunk and threaded outer end of said passage. The end 36 of the rod is also slotted for reception of screw driver whereby the rod may be adjusted longitudinally in the 65 passage. Outwardly of the end of the rod in the passage is a threaded plug 37 which functions in the nature of a lock nut to retain the rod in adjusted position. The plug is readily removed to give access to the rod 70 for adjustment. The inner end of the rod bears against a plunger 19 slidably mounted in the counter-sunk inner end of the passage 20 and the plunger 19 bears against the ball 18, as shown. The device insures a positive 75 seating of the cam for both movements of the plungers.

80 As well shown, the cam 15 also comprises a plurality (three in the present instance) of radial recesses 22 which as shown in Fig. 4 are substantially cylindrical in cross section and which extend inwardly from the side face of the cam and also open into the upper cam face through slots 23 of lesser width where it joins the cylindrical portion 85 of the recess than the diameter of the latter. The sides of the slot 23 as indicated at 90 24 slope outwardly away from each other and towards the upper face of the cam.

95 The cylindrical recesses 22 are adapted to 100

receive the substantially spherical end portions 25 of plungers 26 adapted to slide in longitudinal cylindrical bores 27 in the rotor 2.

5 It will be noted that the spherical ends 25 of the plungers are connected to the main plunger bodies by restricted necks 28 which are lesser in width than the narrowest portions of the slots 23, and this in conjunction with the outwardly sloping sides of side slots 23 permits relative movement between the cam and the plungers in planes transverse to the longitudinal center lines of the cylindrical recesses 22.

10 It is also noted that the construction permits relative movement between the cam and the spherical portions 25 of the plungers longitudinally of the recesses 22. Provision, as described, for these relative movements 15 between the cam and the plunger fully compensates for the changes in the relative positions of these parts due to the inclined position of the cam 15, as shown in Fig. 1 and its rotation about an axis which is inclined 20 to the axis of rotation of the piston 2.

15 The foregoing description will afford a full knowledge to those acquainted with the art of the construction and operation of the improved pump. The cylindrical bores 27 in which the plungers operate are connected with ports 29 and 30 in the walls of the casting 1, which ports respectively connect with channels 31 and 32 extending, in the present instance, through a projection 33 of the casting 1, and these channels 31 and 32 respectively connect with ports 34 and 35 at opposite sides of the extension 33 which are adapted to be respectively connected with a source of supply of the viscous substance 25 from which the artificial silk is formed and the spinneret through which the pump discharges the substance after drawing it in through the port 35.

20 It will be noted that the plungers 26 are rigid throughout their length, and that the compensatory movement between the rotor 2 and the cam 15 is accomplished entirely through an actual relative movement between the cam and those parts of the rotor 25 engaged by the latter.

I claim:

1. A spinning pump comprising a cylinder, a rotor in the cylinder, plungers adapted for longitudinal reciprocation within the rotor, the lower ends of said plungers terminating in spherical portions, a cam adapted to rotate about an axis inclined to the axis of rotation of said rotor and including 55 radial recesses for reception of the projecting spherical ends of said plungers, said recesses extending radially inwardly from the outer edge of said cam and having radial slots opening into said recesses from the face 60 of said cam adjacent to the said plungers,

the said slots being of a less width than the diameters of the spherical end portions of said plungers whereby said plungers are prevented from vertical movement relatively to said cam, but are allowed free lateral movement in said recesses, and means for rotating the rotor in the cylinder. 70

2. In a spinning pump, the combination with a cylindrical casing, of a rotor in said casing having a longitudinal bore, a plunger 75 adapted to operate in said bore, and an actuating member adapted to rotate within the casing about an axis at an angle to the axis of said rotor, said member having a cylindrical recess extending radially inwardly 80 from its edge and having a radial slot opening into said recess from the face of the member adjacent the said rotor, and said plunger having at its outer end a spherical part adapted to fit slidably within said recess and 85 having adjacent thereto a restricted part adapted to pass loosely through the said slot in the actuating member whereby to permit relative movement between the plunger and the actuating member in a plane transverse 90 to the longitudinal axis of said recess.

3. A spinning pump comprising a cylinder, a rotor mounted in the cylinder, plungers adapted for longitudinal reciprocation within the rotor, a plunger-actuating cam adapted 95 to rotate about an axis inclined to the axis of rotation of said rotor, means carried by the rotor for positively preventing movement of the cam toward the rotor, said means adapted to be adjusted to and held in different positions longitudinally of said rotor, and means for rotating the rotor in the cylinder. 100

4. A spinning pump comprising a cylinder, a rotor mounted in the cylinder, plungers adapted for longitudinal reciprocation within the rotor, a plunger-actuating cam seated in the casing and adapted to rotate about an axis inclined to the axis of the rotor, means accessible from the exterior of the pump for regulating the position of the last mentioned means toward and from the said cam, means cooperative with the rotor for positively retaining the cam on its seat, and means for rotating the rotor in the cylinder. 110 115

5. A spinning pump comprising a cylinder, a rotor mounted in the cylinder, plungers adapted for longitudinal reciprocation within the rotor, a plunger-actuating cam seated in the casing for rotation about an axis inclined to the axis of the rotor, manually adjustable means carried by the rotor for retaining the cam on its seat, and means for rotating the rotor in the cylinder. 120

6. A spinning pump comprising a cylinder, a rotor in the cylinder, plungers adapted for longitudinal reciprocation within the rotor, a plunger-actuating cam seated in the casing for rotation about an axis inclined to the axis of the rotor, manually adjustable 125 130

means between the rotor and the cam for retaining the cam on its seat, and means for rotating the rotor in the cylinder.

7. A spinning pump comprising a cylinder, a rotor mounted within the cylinder, plungers adapted for longitudinal reciprocation within the rotor, a plunger-actuating cam seated in the casing for rotation about an axis inclined to the axis of the rotor, manually adjustable means carried by the rotor for exerting a pressure on the cam to retain it on its seat, and means for rotating the rotor in the cylinder.

8. A spinning pump comprising a cylinder, a rotor mounted in the cylinder, plungers adapted for longitudinal reciprocation within the rotor, a plunger-actuating cam seated in the casing for rotation about an axis inclined to the axis of the rotor, means carried by the rotor for retaining the cam on its seat, means providing for manual adjustment of said retaining means to take up wear developing between the parts, and means for rotating the rotor in the cylinder.

25 9. In a spinning pump, the combination with a cylindrical casing, of a rotor mounted in the casing, said rotor having an axial concentric extension projecting through one end of said casing and also having an axial 30 opening extending therethrough, plungers adapted for longitudinal reciprocation within openings provided in and extending longitudinally of the rotor, a plunger-actuating cam seated in the casing at the inner end 35 of the rotor and adapted for rotation on said seat about an axis inclined to the axis of the rotor, a plunger in the inner end of said axial opening arranged to bear against the adjacent face of the cam, a rod mounted in the 40 said axial opening and in contact at its inner end with said plunger and threaded at its outer end in the outer end of said axial opening, said rod being adjustable from the outer projecting extension of the rotor to regulate 45 the pressure exerted by the plunger on the rotor, means for locking the said rod in the adjusted position, and means carried by the projecting extension of said rotor for rotating the rotor in the casing.

50 10. A spinning pump comprising a cylinder, a rotor in the cylinder, plungers adapted for longitudinal reciprocation within the rotor, a cam adapted to rotate about an axis inclined to the axis of rotation of said rotor 55 piston and including radial recesses for reception and retention of the projecting ends of said plungers in which the retained ends of the plungers are freely movable radially of the cam, adjustable means operative between the rotor and the cam for positively preventing movement of the cam toward the rotor, and means for rotating the rotor in the cylinder.

65 11. A spinning pump comprising a cylinder, a rotor in the cylinder, a cam adapted

to rotate about an axis inclined to the axis of rotation of said rotor and including radial recesses and the face of the cam being provided with radial slots which open at their inner sides into the said recesses, plungers adapted for longitudinal reciprocation within the rotor and having spherical extremities adapted to be loosely confined in said radial recesses and joined to the bodies of the plungers by restricted necks which pass through the said longitudinal slots, and means for rotating the rotor in the cylinder.
